UNITED STATES PATENT OFFICE.

FRED O. FISH, OF WINCHESTER, MASSACHUSETTS.

ATTACHMENT FOR GOLF CLUBS.

Application filed May 4, 1927. Serial No. 188,681.

The present invention relates to golf club attachments and is designed to provide a simple and efficient means for indicating the precise path of the club head during 5 that portion of the swing at which the ball is hit.

An object of the invention is to provide an attachment which can be readily applied to the head of the golf club without appreciably increasing the weight or 10 altering the balance or feel of the club, and which will hold a marker projecting below the sole of the club head so as to make a mark upon a flat surface such as a piece 15 of cardboard over which the club is swung. Other objects of the invention are to provide an attachment of the character above referred to which will leave the sole of the club head unobstructed and which will 20 yield as the marker strikes the playing surface and produce an indication mark without liability of injury to the marker or to the holder.

With the above objects in view, the invention 25 consists of the attachment for a golf club hereinafter described and claimed.

Referring to the drawings, Figs. 1 and 2 are perspective views illustrating the preferred form of attachment applied to 30 an iron club; Fig. 3 is a perspective view of the attachment before being applied to the club, and Fig. 4 is a detail cross sectional view illustrating particularly the manner in which the marker holder is 35 guided on the blade of the club.

As illustrated in the drawings, the marker consists of a soft crayon 1 and the holder for the marker consists of a coil 2 formed in one end of a piece of spring wire. This 40 spring wire constitutes a frame which is suitably shaped to support the marker on the club head in the proper position and allow it to yield as it comes in contact with a playing surface. As illustrated, the wire 45 extends upwardly from the holder portion 2 and is then bent downwardly and then upwardly to form a guide adapted to embrace the upper edge of the club head as best shown in Fig. 4. From the bent 50 guiding portion the wire extends substantially at right angles to the marker and at the end remote from the marker is bent to a position so that it will be substantially parallel to the shaft of the club when the 55 attachment is in position on the club. As

a convenient means for securing the wire frame to the club, a spring clip 3 is provided, one end of which is rolled over to form a socket into which the end of the wire frame fits snugly. The clip 3, when 60 the attachment is in position on the club, snugly clasps the neck or shaft of the club just above the head and holds the frame in position while permitting its ready removal.

The manner in which the attachment is used will be obvious. As the club passes over the playing surface at the lowest portion of the swing, the marker which projects below the sole of the club head 70 between the heel and toe, as illustrated in Fig. 4, will come in contact with the playing surface and be held yieldingly in engagement with said surface for a sufficient length of time to indicate by a mark upon 75 the playing surface the direction of travel of the club head. The spring character of the wire frame will permit the marker to yield so that it will not be injured, and the engagement of the guided portion of the frame with the club head will prevent the frame from being displaced with relation to the club head.

Freedom from injury to the attachment 80 is also insured by the fact that the marker is located at the rear of the back face of the club head. Also no portion of the attachment extends across the sole of the club head, which is unobstructed and can be brought forcibly against the playing surface 85 without crushing or bending the attachment. As the crayon wears away, it can be adjusted downwardly by turning it in the holder portion 2 of the frame, the spiral turns of the wire acting to feed the crayon downwardly 90 as it is rotated.

The invention having been thus described, what is claimed is:

1. An attachment for a golf club consisting of a marker holder, and means for yieldingly supporting the marker holder on the club with the marker projecting below the sole of the club head between the heel and toe ends while leaving the sole of the club head unobstructed.

2. An attachment for a golf club consisting of a wire formed at one end as a marker holder and bent to form a guide to fit over the top edge of the club head, and means attached to the other end of the wire for 110

securing the attachment to the club with the marker projecting below the sole of the club head.

3. An attachment for a golf club consisting of a wire formed at one end as a marker holder and bent to form a guide to fit over the top edge of the club head, and a spring clip to which the other end of the wire is attached adapted to clasp the club and hold the marker projecting below the sole of the club head.

4. An attachment for a golf club consisting of a frame provided with a marker holder and formed with a guiding portion to slide on the club head, and means for securing the frame to the club with the marker projecting below the sole of the club head.

5. An attachment for a golf club consisting of a frame provided with a marker

holder, and means for securing the frame to the club with the marker located at the rear of the back face of the club head and projecting below the sole of the club head while leaving the sole of the club head unobstructed.

6. An attachment for a golf club consisting of a frame provided with a marker holder and with a portion adapted to project over the front face of the club head, and means for securing the frame to the club with the marker located at the rear of the back face of the club head and projecting below the sole of the club head while leaving the sole of the club head unobstructed.

In testimony whereof I have signed my name to this specification.

FRED O. FISH.
